United States Patent Office

Des. 217,645
Patented May 19, 1970

217,645

BOAT BUMPER

Hugo Magi, Etobicoke, Ontario, Canada, assignor to
Aqua-Marine Mfg. Limited, Toronto, Ontario,
Canada

Filed Apr. 14, 1969, Ser. No. 16,746

Term of patent 14 years

Int. Cl. D12—14

U.S. Cl. D71—1

The drawing is a perspective view of a boat bumper showing my new design.

The boat bumper shown in the drawing is symmetrical about its longitudinal axis.

I claim:

The ornamental design for a boat bumper, as shown and described.
